UNITED STATES PATENT OFFICE

ELWIN H. KIDDER AND WILLARD E. ERICKSON, OF CHICAGO, ILLINOIS, ASSIGNEES
TO LINK-BELT COMPANY, OF CHICAGO, ILLINOIS, A CORPORATION OF ILLINOIS

CAR DUMPER

Application filed August 1, 1927. Serial No. 209,664.

Our invention relates to improvements in gondola car dumpers and has for one object to provide a new and improved apparatus whereby the car may be positively held on the 5 cradle during dumping. Another object is to provide a new and improved apparatus whereby the car holding clamps may be raised toward and from the car. Another object is to provide a new and improved apparatus whereby the operation of the clamps both for holding and raising and lowering may be at all times automatic. Other objects will appear from time to time throughout the specification and claims.

15 Our invention is illustrated more or less diagrammatically in the accompanying drawings, wherein—

Figure 1 is an end view with parts in section;

20 Figure 2 is a side elevation with parts in section;

Figure 3 is a section along the line 3—3 of Figure 2;

25 Figure 4 is a detail section of the tension release switch;

Figure 5 is a detail of the equalizing mechanism;

Figure 6 is a partial elevation of the side opposite that shown in Figures 2 and 5.

30 Like parts are indicated by like characters throughout the specification and drawings.

It will be understood that in general our car dumper comprises a rotatable cradle and 35 a transfer table carried thereby onto which the car can run which when the cradle commences rotation moves or carries the railroad car laterally to one side of the cradle so as to give a lateral support for the car in the dumping position. Mounted on this cradle are a plurality of car holding clamps movable toward and from the top of the car adjustable in position to compensate for different heights of car with separate means for raising and lowering the clamps with respect to the car and for holding the clamps on the car and for holding the car in place on the cradle during the dumping position.

40 A A are roller rings at the opposed ends of the cradle. They have peripheral tracks A¹

A¹ adapted to ride in and be supported on grooved rollers A² A². These rollers are mounted in pairs on the rocker arms A³ which arms are pivoted on brackets A⁴, the brackets being carried by foundation beams A⁶ resting on the foundation walls A⁷. Extending laterally between the roller rings are a plurality of supporting beams A⁸. Extending upwardly from these supporting beams are vertical members A⁹ associated with other transverse beams A¹⁰ A¹¹ A¹² to make a cradle structure joining the two roller rings. The cradle thus is formed of the two end plates or roller rings with the girder structure joining them, there being a central aperture into which the car may pass.

Along one side of the cradle is a car side engaging mat B made up of a plurality of horizontally disposed elements B¹ B¹. At the bottom of the cradle is a transfer table B² having tracks B³ on which the car can travel. B⁴ is an elevated rail adjacent one of the tracks B³ so as to prevent lateral movement of the car wheels and axle which might otherwise slip off the rail when the car is in the dumping position. This transfer table extends throughout the entire length of the cradle and projects laterally therebeyond sufficiently for the rails B³ to abut on fixed tracks B⁵ on which the car may approach or leave the dumper. B⁶ B⁶ are a plurality of transverse tracks on the cradle upon which travel rollers B⁷ to carry the transfer table and permit lateral movement. Under some conditions extending downwardly from the opposed ends of the transfer table are brackets B⁸ having rollers B⁹ adapted to engage stops B¹⁰, one at each end of the foundation so that as the cradle returns to its starting position the roller B⁹ engaging the stop B¹⁰ limits the movement of the transfer table and insures its return into alignment with the approach tracks. B¹¹ is a compression spring associated with a guide rod B¹² and abutting at one end on a collar B¹³ on the rod; at the other end on a sleeve B¹⁴ slidable on the rod and engaging part of the transfer table. This rod is anchored on the table so that when in the position shown in Figure 1 the spring is under compression. In Figure 10

3 it will be noted that the transfer table has been moved over toward the opposed side of the table, and the spring is expanded, the purpose of this spring being of course to insure movement of the transfer table laterally across the table at the beginning of the cradle rotation so that the car side is brought against the cushion or pad B before the clamps take hold.

10 B¹⁵ are rollers mounted in the foundation adapted to engage the opposed ends of the transfer table to limit its lateral movement and maintain it in proper spaced relation longitudinally with respect to the approach 15 tracks.

C C are cables wound about the roller frames and dead ended thereon by means of tie-rods C¹ sliding in brackets C² associated with adjusting nuts C³ and springs C⁴. The 20 bight is wound about a drum C⁵ which drum is rigidly mounted on the shaft C⁶, which shaft also carries a gear C⁷ driven through a train of gears as indicated by the motor C⁸, the motor being reversible to move the cradle. 25 into and out of the dumping position. It will be noted that the motor C⁸ is at the center of the shaft in line with each roller ring, the motor and train of gears being located intermediate the ends of the cradle. 30 C⁹ is a solenoid brake associated with the motor. The means for controlling the motor are not here shown since they may take the form of any suitable drum type controller manipulated by the operator whereby 35 he can stop and start the rotation of the cradle and rotate in either direction, the solenoid brake operating to go on and lock the parts in position wherever they are left by the operator's manipulation of the control, the arrangement being the usual one whereby when the current is on the motor, the brake is off and when the current is turned off the brake goes into operation.

D D are a series of contiguous hoppers 45 located beneath the cradle and adapted to receive the discharge from the car. D¹ D² are chutes discharging from the hoppers onto belt conveyers D² which conveyers carry material discharged from the car up to any 50 suitable point for disposal.

Extending upwardly along that side of the cradle opposed to the pad or mat which receives the car are two upright stanchions E. These upright stanchions E carry 55 brackets or guideways E¹ in which are slidably mounted clamp slides E². These clamp slides have projecting laterally from them short clamp arms E³ rigid therewith and pivoted with them and extending across the 60 car on clamp members E⁴. The short clamp engages the top of the car on the inner side, the long clamp engages the top of the car on the far side. The pivoted member E⁴ is associated with a stop E⁵ when the clamp 65 slide is raised so that the clamps are out of

contact with the car, the long clamp has its car engaging elements slightly below the car engaging element of the short clamp. Thus when the clamp settles down on the car the pivoted long clamp engages first and then 70 the rigid short clamp so as to insure taking hold of the car independent of variations in height or variations of the positions of the parts.

E²⁵ is a sheave at the upper end of the side 75 member E. A cable is dead ended on the clamp slide E², passes up over this sheave down along guide sheaves E⁶ E⁷ E⁸ to the bottom of the upright. From the sheave E⁸ it passes over a transverse sheave E⁹ on the 80 roller ring, thence to a sheave E¹⁰ also on the roller ring and then back to the lifting carriage E¹¹. This lifting carriage is provided with rollers E¹² E¹³ movable in a peripheral circular track E¹³ and has an arm E¹⁴ adapted to engage the stop E¹⁵ on the foundation 85 so that when the parts are in the position shown in Figure 1 the cable is drawn out between the sheave E¹⁰ and the stop holds the carriage to raise the clamps away from the car. When in the position shown in Figure 3 it will be noted that the carriage has been allowed to return toward the sheave E¹⁰ thus permitting the clamps to settle on the car. This takes place on the beginning 90 of the cradle rotation and as the cradle rotates in a counter clockwise direction from the position shown in Figure 1 as long as the weight of the clamps has not been supported by the car movement of the cradle merely shortens the rope drawn out between E¹⁰ and the carriage. Further movement after the clamps have settled down causes the carriage to leave the stop as it rotates with the cradle, any suitable friction means being 95 provided between the carriage and the cradle to prevent its further uncontrolled movement. There are thus positive means provided for raising the clamps away from the car 100 as the car returns to its working position 105 from the dumping position.

In order to hold the clamps down on the car and to support the weight of the car, cables are provided extending about each 110 pair of clamps and in order to insure that tension is the same on both ends, equalizing means are provided between the free ends of the cables, the driven ends being both wound upon a drum driven by a motor.

The equalizing means comprise links F 115 F¹ pivoted on the cradle. Sleeves F² F² are pivoted on these links. At their other ends these sleeves are pivoted on triangular bell crank levers F³ F³. A tie-rod F⁴ associated with springs F⁵ F⁵ at either end of the tie-rod contained within the sleeves F² provides flexible means for taking up irregularities and taking care of stretch of the cables, change of temperature, and the like. It will be evident that owing to this structure subject 120 125 130

only to the flexibility of the springs, the two bell crank levers must travel in the same direction so that as one cable pays out, the other is drawn in. These bell crank levers 5 are mounted on brackets F⁶ downwardly depending from the cradle. The other arm of each bell crank lever carries an equalizing lever F⁷, there being cables F⁸ F⁹ anchored on the two opposed arms of the equalizing levers associated with turn buckles F¹⁰ to take up slack. F¹⁰ is a thimble holding two cables in proper alignment though it will be understood that they are free to have some movement longitudinally of each other with respect to the thimble. These cables F⁸ pass 15 up over parallel sheaves F¹¹ on the outboard end of the long crank, thence inwardly over parallel sheaves F¹² on the sheave slide, thence over the tension limit pulley F¹³ to a winding drum F¹⁴ where each cable is separately dead ended.

The tension limit pulley F¹³ comprises an axle shaft G mounted on sliding pins G¹ in bearings G². Springs G³ resist movement of 25 the pin G¹ from the position shown in Figure 4, the tension on the cable tending to move the pin in such direction that the free end G⁴ thereof may engage the electric switch G⁵, the arrangement being such that only after 30 the tension in the cable has reached a predetermined point is this switch closed to stop the operation of the clamp driving motor.

The clamp driving motor is shown diagrammatically at G⁶. After it has once started it continues to operate drawing down on the clamps until the car is firmly seated and until such pressure has been exerted by the clamps on the car to cause the tension in the cable, compress the spring and operate the switch. As soon as the switch is operated 40 the current is turned off from the motor and simultaneously the solenoid brake G⁷ or the equivalent goes into operation by permitting the brake spring to seat the brake, thus holding the tension on the clamps. If at any 45 time during operation the tension on the cable should drop as for instance if a piece of rock or coal had been caught between the clamp and the top of the car and was subsequently crushed, the instantaneous reduction in pressure would immediately permit the spring to force the sheave back, thus opening the switch, throwing out the solenoid brake, overcoming the spring tension which holds 50 the brake and starting the motor. The motor would operate to take up the slack until the tension in the cable had again reached the predetermined point when the brake would go on, the motor would go off and the cable and clamp would remain in tight holding position.

There is one of these drums F¹⁴ at each end 65 of the cradle. The drums are mounted rigidly on shafts H. Each shaft has a gear H¹ in mesh with a pinion H² on a through shaft H³,

there being a pinion H² at each end of such through shaft and a gear H⁴ intermediate the ends. This gear is driven through a train of gears as indicated from a motor G⁶, the motor having associated with it the solenoid brake G⁷ above referred to. The operation of the clamping motor is entirely automatic.

I is a switch box mounted on the beam A⁶ having a plurality of switch levers I¹ and I². I³ is a starting trigger adapted when the cradle is rotated through an angle of say ten degrees to throw the lever I¹ and start the motor. The motor starts pulling the clamps down against the tension of the clamp lifting cable. The normal unloaded speed of the motor will be greater than the speed at which the clamp lifting rope is paid out but not enough greater to cause the tension switch to operate. As soon as the clamps settle against the car, the motor will build up its tension in the cable and stop at some predetermined point holding the clamps in position. On the return movement the stop I⁴ will engage the switch lever I² at about thirty-five degrees from horizontal, will operate the solenoid 70 brake without operating the motor. From this time on the clamp locking rope and motor are free to turn and they are turned into the starting position by the engagement of the carriage and stop leaving the mechanism 75 80 85 90 95 in the original starting position.

During the time that the motor current is turned on that is from the time when the starting switch I¹ is operated to throw the current on the motor to the time when the releasing switch I² is operated to release the solenoid brake, the only thing that will stop the motor will be the cable tension control switch. During the remainder of the time, that is when the cradle is in the upright or generally upright position, the current is off the motor but on the solenoid switch so that the clamps are free to be moved and held in position by the clamp raising mechanism. The electric details are not shown since they 100 105 110 form no part of our present invention.

J is a ladder whereby the operator may get to the top of the structure.

The free car side contacting end of the clamp is laterally disposed as indicated to form what is technically known as a pad to engage the side of the car and exert pressure downwardly thereupon to hold the car upon the track.

We claim:

1. In a car dumper, a cradle and means for rotating it, clamps adapted to hold the car in place in the cradle during rotation, a motor for seating the clamps against the car and separate positive independent of gravity 115 120 125 means for raising the clamps out of contact with the car.

2. In a rotary car dump, a clamp adapted to move toward and from and hold the car in position, clamp holding means comprising 130

a motor driven drum, a plurality of separate cables arranged in parallel and wound about the drum, sheaves on the clamps over which the cables travel and an anchorage for the 5 ends of the cables removed from the drum including an equalizing lever, the ends of the cables being anchored to the opposed ends of the equalizing lever.

3. In a rotary car dump, a clamp adapted 10 to move toward and from and hold the car in position, clamp holding means comprising a motor driven drum, a plurality of separate cables arranged in parallel and wound about the drum, sheaves on the clamps over which 15 the cables travel and an anchorage for the ends of the cables removed from the drum including an equalizing lever, the ends of the cables being anchored to the opposed ends of the equalizing lever, and a thimble associated with the cables adjacent their end to hold that part of the cables which pass over the sheaves in substantial parallelism.

4. An anchorage for cables for car dumpers comprising a pair of opposed bell crank 25 levers, a cable dead ended on one arm of each bell crank, an adjustable connection between the remaining arms of the opposed bell crank levers, yielding means interposed in the connection between the bell crank levers, said 30 yielding means comprising a sleeve pivoted at one end on the bell crank lever, a rod slideable within the sleeve, a compression spring interposed between one end of the sleeve and the rod for resisting longitudinal movement 35 of the sleeve with respect to the rod, and a link pivotally supporting that end of the sleeve removed from the bell crank lever.

5. In a car dumper, a cradle, car clamps thereon, holding means for the clamps comprising 40 a plurality of cables associated with each clamp, a drum upon which the adjacent ends of each cable are wound, equalizing levers to which the free ends of each cable are anchored, a bell crank lever upon which each 45 equalizing lever is mounted and an equalizing connection between the bell crank levers associated with adjacent clamps whereby the tension in all the cables is kept uniform.

6. In a car dumper, a plurality of car holding 50 clamps adapted to extend entirely across a car, a holding cable for each clamp, a fixed anchorage for one end of each cable, a drum about which the unanchored end of each cable is wound, a single motor and a driving connection 55 between it and all the drums whereby it exerts a tension on all the cables simultaneously, equalizing means between all the cable anchorages whereby the tension in all the cables is the same.

60 Signed at Chicago, in the county of Cook and State of Illinois, this 29th day of July, 1927.

ELWIN H. KIDDER.
WILLARD E. ERICKSON.
